Cooper, Stern and Dunham

UNITED STATES PATENT OFFICE.

SWEN R. SWENSON, OF SOUTH ORANGE, NEW JERSEY, ASSIGNOR TO MULTIPLE ELECTRIC PRODUCTS COMPANY, INC., OF NEW YORK, N. Y., A CORPORATION OF NEW YORK.

SEPARABLE PLUG.

Original application filed February 20, 1922, Serial No. 537,770. Divided and this application filed July 9, 1923. Serial No. 650,333.

To all whom it may concern:

Be it known that I, SWEN R. SWENSON, a citizen of the United States of America, residing at South Orange, in the county of 5 Essex and State of New Jersey, have invented certain new and useful Improvements in Separable Plugs, of which the following is a full, clear, and exact description.

My invention relates to separable attachment plugs for use in those cases where it is desirable to connect electric translating devices, for example, an electric iron, in an electric circuit terminating in a socket, such as a screw socket for an electric lamp bulb 15 having a screw base.

The object of my invention is to compel the operator when connecting or disconnecting the plug and the socket to first separate the member carrying the wires leading 20 to the translating device from the other member of the plug, thus providing increased safety in the making of the connections above referred to and preventing the twisting of the wires between the separable 25 plug and the translating device and obviating the wear and tear on the wires and terminals which heretofore has been caused by the twisting of the wires in the act of screwing connecting plugs into the socket.

30 I accomplish the object of my invention in the present embodiment, by providing the member carrying the flexible lead wires with a revolvable cap or sleeve completely covering the outer face of said member and the 35 sides thereof and extending beyond the sides of the member to be inserted in the socket when the parts of the separable plug are assembled.

By way of example of the application of 40 my invention I have chosen to illustrate it in connection with a socket of the screw type, but it will be understood that the invention is applicable to other types of sockets.

45 In the accompanying drawings,

Fig. 1 is a vertical section of one form of my new separable plugs assembled and showing the revolvable cap for preventing the insertion or withdrawal of the socket 50 engaging member into or out of the socket while the members of the separable plug are assembled; and

Fig. 2 is a bottom view of the member

carrying the wires leading to a translating device.

In the drawings, 1 is a screw plug engaging with a suitable screw socket (not shown) said plug being provided with contact members 2 and 3 for engaging with the contacts of the socket, and 4 is the removable member of said plug in which is mounted extension terminals 5 and 6 engaging with the contact members 2 and 3 of the plug 1. The terminals 5 and 6 are secured to the member 4 by screws 7 and 8, as shown in Fig. 2, 60 and wires 9 and 10 are connected thereto and pass through a tube 11 and thence to a suitable translating device. A cap piece, 12, is mounted on the outer face of the removable member 4 and held in place there- 65 on by the circular flange of the tube 11, the cap piece being of any suitable material, as iron, hard rubber, etc., as desired, and being free to revolve. As shown in the drawings, the cap piece 12 covers the outer face and 70 sides of the member 4 and as much of the sides of the member 1 as desired to serve the purpose contemplated.

In the utilization of a structure such as that described above, it is apparent that, due 75 to the presence of the freely revolving cap-piece 12, an operator wishing to connect the plug into a socket must first separate the member 4 from the member 1, as by a pulling action, whereupon the plug 1 is screwed 80 into the socket and thereafter the member 4 is pushed into the plug 1, completing the connection. When it is desired to disconnect the separable plug 1—4 from the socket 85 it is apparent that, due to the presence of the revolvable cap-piece 12, the operator must first pull the member 4 out from the plug 1, whereupon the plug 1 is unscrewed 90 from the socket.

This application is a division of my ap- 95 plication, Ser. No. 537,770, filed Feb. 20, 1922.

It is to be understood that the invention is not limited to the specific constructions herein described, but can be embodied in 100 other forms without departure from its spirit.

I claim:

1. A separable socket plug comprising a socket engaging member and lead wire car- 105 carrying member, and means comprising a piv-

- totally mounted enclosing member in operative relation to said plug members for preventing the entry into or withdrawal of the assembled plug from a socket.
- 5 2. A separable socket plug comprising a socket engaging member and a lead wire carrying member, and a freely movable cap pivoted on said plug and enclosing the normally exposed portions of said assembled plug members.
- 10
3. A separable socket plug comprising a socket engaging member and a lead wire carrying member, and a freely revolvable cap on said wire carrying member enclosing the normally exposed portions of said assembled members.

In testimony whereof I hereto affix my signature.

SWEN R. SWENSON.
